UNITED STATES PATENT OFFICE.

ANTHONY P. HINSKY, OF BROOKLYN, NEW YORK.

STARTING DEVICE FOR INTERNAL-COMBUSTION ENGINES.

1,013,293.

Specification of Letters Patent.

Patented Jan. 2, 1912.

Application filed May 2, 1911. Serial No. 624,618.

To all whom it may concern:

Be it known that I, ANTHONY P. HINSKY, a citizen of the United States, and residing at Brooklyn, in the county of Kings and State of New York, have invented certain new and useful Improvements in Starting Devices for Internal-Combustion Engines, of which the following is a specification, such as will enable those skilled in the art to which it appertains to make and use the same.

This invention relates to internal combustion engines such as are usually employed in connection with automobiles and various other devices or forms of apparatus, and said invention relates particularly to what are known as the "cranking" or starting devices of engines of this class; and the object of the invention is to eliminate the danger of what is known as the "back-kick" of the crank shaft by which the engine is started, which object is accomplished by means of the construction hereinafter described and claimed.

The invention is fully disclosed in the following specification of which the accompanying drawing forms a part, in which the separate parts of my improvement are designated by suitable reference characters in each of the views, and in which:—

Figure 1 is a view showing the crank shaft of an internal combustion engine, the fly-wheel mounted thereon and my improvement used in connection therewith, and the construction of which is shown in section, and; Fig. 2 a section on the line 2—2 of Fig. 1.

In the drawing forming part of this specification, I have shown at a the crank shaft of an internal combustion engine, which shaft is provided with the usual fly-wheel a^2 and, in the practice of my invention I provide a supplemental crank shaft b which passes through and is supported in a bracket sleeve c having an angularly arranged supporting plate c^2 rigidly secured to a part c^3 of the frame of the engine or the framework of an automobile in which the engine is used, and the sleeve c and supplemental shaft b are in axial line with the crank shaft a and the supplemental shaft b is longitudinally movable through said sleeve.

The end of the crank shaft a is provided on one side thereof with a lock tooth or projection a^3 and the adjacent end of the

supplemental shaft b is provided with a head b^2 which is rigidly secured thereto or thereon and is provided with a lock tooth or projection b^3 which corresponds with and is adapted to operate in connection with the lock tooth or projection a^3 on the shaft a . The end of the sleeve c opposite the fly-wheel a^2 is provided with a recess b^4 in which is placed a spiral spring d through which the supplemental shaft b also passes, and mounted on the outer end of the supplemental shaft b is a crank arm e composed of two similar parts secured together as shown at e^2 by bolts or screws, or in any desired manner, and the form of the separate parts of the crank arm is such as to form therein a longitudinal chamber e^3 . Mounted on the outer end of the supplemental shaft b within the crank arm e is a gear f which is keyed to said shaft, and the free end of the crank arm e is provided with a spindle g which passes therethrough and is provided with a handle member g^2 which is keyed thereto, and mounted on said spindle within the crank arm e is a gear f^2 which is secured to said spindle and which is similar to the gear f , and between the gears f and f^2 are two other gears f^3 and f^4 which mesh with the gears f and f^2 , respectively, and with each other.

Secured to the inner side of the end portion of the crank arm e through which the supplemental shaft b passes is a ratchet wheel h , said ratchet wheel being secured to said arm, in the form of construction shown, by screws h^2 , and the spring d bears on said ratchet wheel or on a washer h^3 placed between said wheel and said spring, and said spring normally operates to hold the supplemental shaft b in its outermost position, as shown in Fig. 1, but said shaft may be forced inwardly so that the lock tooth or projection b^3 on the head b^2 thereof will engage the lock tooth or projection a^3 on the crank shaft a when said shaft is turned.

Mounted on the outer side of the supporting plate c^2 of the bracket sleeve c are a plurality of pawls i which operate in connection with the ratchet wheel h and these pawls, in the form of construction shown, are four in number and are arranged in the arc of a circle around and above said ratchet wheel, and springs i^2 are employed in connection with said pawls so as to hold them at all times in position for operation in connection with the ratchet wheel h , and when

the supplemental shaft b is in its outermost position, as shown in Fig. 1, the pawls i will engage the ratchet wheel h or the teeth thereof only at the inner side of said wheel, 5 as shown in said figure, but when said shaft is forced inwardly so as to operate the crank shaft a , the pawls i will be fully in engagement with the teeth of the ratchet wheel or in position to fully engage said teeth, and 10 said pawls are also arranged as shown in Fig. 2 so that they will fully engage the teeth of the wheel h at different times in its revolution or in such manner as to permit only a slight backward movement of the 15 shaft of said wheel and of the crank arm e .

It is a well known fact that in starting or "cranking" internal combustion engines there is frequently a quick backward rotation or what is known as a "back-kick" of 20 the crank shaft or the starting shaft of the engine and this results in a quick backward movement of the crank arm which frequently results in serious injury to the operator, but with my invention this danger to 25 the operator in starting or "cranking" engines of the class specified is entirely done away with, as will be seen from the foregoing description, the accompanying drawing forming part of said description and the 30 following statement of the operation of "cranking" or starting the engine.

With my improvement the operation of starting or "cranking" the engine is as follows: The operator first firmly grasps the 35 handle g^2 and by means thereof and the crank arm e forces the supplemental shaft b inwardly against the operation of the spring d until the locking tooth or projection b^2 on the head b^2 of said shaft is in position to 40 engage the corresponding tooth or projection a^3 on the shaft a . The crank arm e is then given a quick turn to the right and this operation turns the shaft b and the shaft a in the usual manner. If, during this operation 45 the operator retains a firm grip on the handle g^2 , all the gears in the crank arm will be prevented from turning and consequently the shaft b must turn, and this movement of said shaft is transmitted to the 50 crank shaft a of the engine. If, in this operation of starting the engine there should be a reverse movement of the shaft a , the result would be as follows: The shaft b would be reversed and the gear f would be 55 turned thereby and the series of gears in the crank arm would turn including the gear f^2 and its spindle g and handle g^2 , but the crank arm, itself, would remain motionless; being held by the ratchet h , and no injury 60 would result to the operator.

In order that there may be no doubt as to the engagement of one or more of the

pawls i with the ratchet wheel h the said pawls are so arranged that they will operate at different intervals on the ratchet h , as 65 clearly shown in Fig. 2, and at the end of each "cranking" operation the shaft b is thrown out of engagement with the shaft a by the spring d , as will be readily understood. 70

Having fully described my invention, what I claim as new and desire to secure by Letters Patent, is:—

1. A cranking apparatus for internal combustion engines consisting of a supplemental shaft mounted in axial line with the crank shaft of the engine and movable toward and from the same and adapted to engage the same, a spring normally holding said supplemental shaft out of engagement with the 80 crank shaft, a crank arm mounted on the outer end of the supplemental shaft and provided with an internal chamber, a gear mounted on said shaft within said chamber and keyed to said shaft, a handle spindle 85 mounted in the outer end of said crank arm, a gear mounted on said spindle within said arm and keyed to said spindle, intermediate gears mounted in said arm and meshing with said first named gears and with each 90 other, a ratchet wheel secured to the inner side of the said arm where the supplemental shaft passes therethrough and through which said supplemental shaft passes, and a plurality of suitably supported pawls adapted 95 to engage said ratchet wheel.

2. A cranking apparatus for internal combustion engines comprising a longitudinally movable shaft mounted in axial line with the crank shaft of the engine and adapted to 100 engage the same, a tension device for holding said shaft out of engagement with the crank shaft, a hollow crank arm mounted on the outer end of said shaft, a handle spindle mounted in the free end of said arm, 105 gears mounted on said shaft and on said handle spindle within said arm and keyed to said shaft and to said spindle, intermediate gears mounted in said arm and meshing with said shaft and spindle gears and with each 110 other, a ratchet wheel secured to the inner side of the inner end of said arm and through which said shaft passes, and spring operated pawls normally in engagement with said ratchet in different operative positions. 115

In testimony that I claim the foregoing as my invention I have signed my name in presence of the subscribing witnesses this 29th day of April 1911.

ANTHONY P. HINSKY.
